UNITED STATES PATENT OFFICE

2,503,669

ELECTRICAL PUSH-BUTTON DEVICE

Walther Hauerslev, Copenhagen, Denmark

Application November 4, 1947, Serial No. 783,895
In Denmark November 14, 1946

2 Claims. (Cl. 74—503)

1

The present invention relates to an improvement in electrical push button devices of the kind, comprising a number of slidably mounted setting members, arranged to alternately set a corresponding number of electrical switches and to be alternately operated each by means of a separate push button.

In push button switches of the kind referred to the setting members are ordinarily engaged each by an individual spring, which when the setting member is released after having been operated to close the switch controlled by same, causes a return movement of the setting member to an initial position. This movement is abruptly stopped by a fixed stop and the heavy stroke of the setting member against this stop produces an undesired noise and is inclined to cause mechanical vibration of parts of the wireless receiver in combination with which the push button is used. Also these vibrations may have an injurious effect on the receiver.

The purpose of the present invention is to avoid the said abrupt stopping of the setting member and to this end the said spring, which may be a helical spring or a U-shaped spring, is according to the invention inserted in a tensioned condition between two fixed abutments which are so located relatively to two further abutments, which are disposed on the setting member or on a separate member connecting the setting member to its push button, that the two ends of the said spring engage opposite ends of a slit in the setting member or the said separate member, so that one end of the spring will be displaced together with the setting member, when operated to close the switch controlled thereby. Thus a compression of the said spring results so that the spring when the setting member is released from the position, in which it closes the said switch, will move the setting member back until the said end of the spring is caught by one of the fixed abutments, whereafter the setting member by its own inertia will continue its own return movement and during this movement carry along the other end of the spring, thus causing the spring to be again tensioned and to retard the backward movement of the setting member and to stop the latter without any shock effect.

On the drawing

Fig. 1 is a side elevation partly in section of a mechanism according to the invention, for carrying the setting member of a push button switch back to its non-operated position, and

2

a modified embodiment of a restoring mechanism, in which the spring causing the return movement of the setting member is a V-shaped resilient leaf spring.

5 In Fig. 1, 1 is a slidable setting member of a push button device for instance for alternately connecting different tuning coils of a wireless receiver in the tuning circuits thereof. Each setting member comprises a vertically disposed metal plate which is adapted to be connected to a removable part 16 of an electrical switch, having movable contacts 20. This switch may be of any suitable construction and is arranged to be closed by displacement of the setting member 1 in a direction indicated by the arrow shown in Fig. 1, from the position shown in full lines in Fig. 1 to a position in which a projection 3 of one edge of the setting member assumes the position shown in dotted lines 3' in Fig. 1, in which position the setting member is locked by a locking member 2, the construction and control of which form no part of the present invention. The locking member 2 is released from engagement behind the projection 3 on the setting member 1 by manually rotating the locking member about a pin 4.

10 The setting member 1 is moved back from the locked position by means of a helical spring 5, which is inserted in an opening 6 in the setting member so that the ends of the spring abut against opposite edges 7 and 8 in said opening 6. Opposite to each of these said edges two fixed abutments 9 and 10 are disposed, which abutments may be formed as two rails each having a U-shaped cross section and being provided with a slit in which the setting member is guided. When the setting member assumes the position shown in full lines each end of the helical spring engages or almost engages one of these fixed abutments 9 and 10 respectively.

15 When the setting member 1 is moved in the direction indicated by the arrow in Fig. 1 the spring is compressed and shortly before this movement is terminated the setting member is automatically locked by the locking member 2.

20 If this locking member is released the setting member is moved back by the action of the spring 5, and when the right-hand end of the spring, see Fig. 1, during this backward movement engages the stationary abutment 10, the accelerating effect of the spring 5 upon the setting member ceases, and at the same time the edge 7 of the opening 6 engages the opposite end of the spring whereafter the latter during the continued backward movement of the setting member 1 is com-

pressed under the influence of the inertia of the said member. This compression of the spring causes the latter to damp the continued backward movement of the setting member and to stop it without any material shock effect.

The embodiment shown in Fig. 2 differs from that of Fig. 1 in that the spring 5 is substantially a V-shaped rod or leaf spring which at its central portion is mounted on a fixed support 11, e. g. by means of a few spring windings surrounding a pin 14 on the support 11, whereas the ends of the said spring extend through a longitudinally disposed slit 12 in a stationary rail 13, which is disposed transversely of the moving direction of the setting member, and through the opening 6 in the setting member 1 and through a slit 15 in the movable switch part 16.

The openings or slits 6 and 12 are so arranged that the ends of the spring abut or approximately abut opposite edges in both of said openings or slits when the setting member is in its non-operative position as shown in Fig. 2.

If the setting member is moved in the direction indicated by the arrow in Fig. 2 in order to displace the switch part 16 the locking member 2 will move down behind a projection 3 on the setting member 1 and thereafter retain the same in the position to which it is moved. At the same time the right-hand end of the spring in Fig. 2 is bent in the moving direction whereas the left hand end of the spring in Fig. 2 remains in the position shown in Fig. 2, that is in contact against one of the edges in the slit 12 of the rail 13. If the locking member 2 is released from the projection 3 the spring 5 will carry the setting member 1 back to the position shown in Fig. 2 since from its contracted condition the spring will expand to the position shown in Fig. 2. During the subsequent continued backward movement of the setting member due to its inertia the rear edge 17 of the opening 6 will engage the left hand end of the spring in Fig. 2 and carry this end forward, so that the spring damps the backward movement of the setting member and stops it without a shock effect.

By properly adjusting the tension of the spring it is possible to operate the mechanism practically noiselessly.

Having now particularly described and ascertained the nature of my invention and in what manner the same is to be performed I declare that what I claim is:

5 1. In an electrical switching device the combination of a switch actuating member mounted for sliding movement between an operated and a non-operated position and having a window provided therein, releasable means for locking said switch actuating member in said operated position, two fixed abutments in positions substantially flush with the ends of said window in the non-operated position of said switch actuating member, and biased compressional spring means mounted in a position to engage both between said two fixed abutments and between the ends of said window.

20 2. An electrical switch device comprising a switch actuating member slidably mounted and having an opening therein, releasable means for locking the switch actuating member in one position, a pair of fixed abutments provided flush with the ends of the opening in another position of the switch actuating member, and biasing means mounted to engage between the fixed abutments and between the ends of the opening.

WALTHER HAUERSLEV.
